UNITED STATES PATENT OFFICE.

STANLEY M. GOLOMBOWSKI, OF MILWAUKEE, WISCONSIN.

AUTOMOBILE SIGNAL SWITCH.

Application filed September 12, 1924. Serial No. 737,385.

This invention relates to automobile signals.

Objects of this invention are to provide an automobile signal which is not complicated, which is extremely sensitive and will respond to any disturbance of the car after the signal has been set, which may be quickly set and unset by an authorized person, and which will respond to any jar of the car either from starting the engine, bumping the car, stepping on the running board or other slight disturbances of this type, and which, when disturbed, will continue to sound or actuate any type of signal.

15 Embodiments of the invention are shown in the accompanying drawings, in which:—

Figure 1 is a vertical sectional view through one form of the device showing diagrammatically the connection to the signal 20 battery and associated parts.

Figure 2 is a view corresponding to Figure 1 showing the device in operative position.

Figure 3 is a fragmentary view of the 25 lower portion of the device showing a modified form.

Figure 4 is a side elevation of the structure shown in Figure 3.

The device comprises a metal casing 1 having a top portion 2. This metal casing carries an insulating block 3 which is provided with a depressed cup shaped recess 4. The recess normally receives a steel ball 5, as shown in Figure 1 when the device is 35 inoperative. This ball is adapted to be raised from the recess by means of a plunger 6 reciprocally mounted within the block 3 and projecting downwardly therefrom. The lower end of the plunger carries a transverse 40 pin 7 which fits within grooves 8 formed in supporting downwardly extending lugs 9. A helical spring 10 loosely surrounds the plunger and urges it downwardly. The lower end of these lugs 9 support a short 45 transverse shaft 11 having a manipulating lever 12. This shaft rigidly carries a cam 13 which is provided with a projecting portion having a flat face 14. Thus when the lever 12 is rotated into the position shown in Figure 2, the plunger 6 is elevated and its lower end rests upon the flat face 14 of the cam.

50 The upper end of the plunger is provided with a concaved face 15 (see Figure 2) upon 55 which the ball 5 rests when such plunger is elevated.

Immediately surrounding the cavity 4 in the insulating blocks 3 a ring like slanting contact plate 16 is provided. This contact plate is provided with a projecting tongue which is connected by means of conductor 17 with a horn or other sounding or signal device 18. It is to be noted that the projecting tongue of the dished ring 16 extends through an aperture in the metal casing 2 65 and furnishes a ready means of connection to the horn. The other terminal of the signalling device being grounded, as shown. One of the supporting lugs 9 is connected to one end of a battery 19, the other end of 70 such battery being grounded as diagrammatically shown in Figure 1.

It is preferable to locate the signalling apparatus in a hidden portion of the car with the lever 12 hidden but within easy 75 access of the driver. The horn and battery may be the usual horn and battery employed in the car or, if desired, a hidden horn and a hidden battery may be employed so that the entire system is hidden.

80 The operation of the apparatus is as follows:—when the driver leaves his car he elevates the lever 12, as shown in Figure 2, thus setting the device. The slightest jar will cause the ball 5 to fall from the top of 85 the plunger 6 and such ball will then rest, as shown in dotted lines in Figure 2, against the contact ring 16 and the plunger 6, thus completing the electrical circuit of the apparatus. In fact from actual experience it 90 has been found that merely stepping upon the running board will serve to unseat the ball and sound the alarm. Further than this, the jar incident to starting the engine or moving the car will also unseat the ball. 95 Further than this if the car is bumped by another vehicle, the ball is dislodged and the signal sounded. When the ball rests in the socket 4, as shown in Figure 1, any bouncing of the ball upwardly will not close 100 the circuit for the reason that the ball cannot bridge the gap between the retracted plunger 6 and the contact ring 16.

105 In the form shown in Figure 3, the same general construction is employed with the exception that the handle 12 and the shaft 11 is omitted. In place of this, the barrel 20 of a lock 21 forms the shaft for supporting and operating the cam 13. This lock may be controlled by means of a key carried 110 by the driver and insertable in the keyhole 22 of the barrel 20, as shown in Figure 4.

Thus no one but an authorized person may set the device although he may know of the secret positioning thereof.

It will thus be seen that an extremely sensitive signal device has been provided which is very compact, which is easily hidden and mounted within an automobile, and which will respond to any disturbance and will continuously sound or give a signal until resetting by an authorized person.

Although the invention has been described in considerable detail, it is to be understood that the invention may be variously embodied and is, therefore, to be limited only as claimed.

I claim:

An automobile signal comprising a casing, an insulating block carried thereby and having a recess upon its upper side, a ball adapted to seat within said recess under normal conditions, an annular slanting contact ring surrounding said recess and spaced therefrom a slight distance, said ring slanting

downwardly towards said recess, said casing being formed in two distinct portions carried and operated by said insulating block, one of said portions being rigid with said slanting ring, a plunger having a concave upper end, said plunger slidably passing through said block and adapted to be projected upwardly into said recess, a pair of supports carried by said block and extending downwardly therefrom, said supports having slots therein, a pin carried by said plunger and guided within said slots, a spring urging said plunger downwardly, a cam mounted between said supports and adapted to elevate said plunger, and key controlled locking means for operating said cam.

In testimony that I claim the foregoing I have hereunto set my hand at Milwaukee, in the county of Milwaukee and State of Wisconsin.

STANLEY M. GOLOMBOWSKI.
